UNITED STATES PATENT OFFICE

2,005,939

REFRIGERATOR RACK

Charles L. Hibbard, Jr., Brookline, Mass., assignor to Old Colony Distributing Company, Inc., Boston, Mass., a corporation of Massachusetts

Application May 13, 1933, Serial No. 670,853

3 Claims. (Cl. 211—74)

This invention relates to refrigerators and is more especially concerned with apparatus for supporting containers in the food compartment where they will be kept cool.

5 The presence of bottles in a cooling chamber is a source of considerable annoyance, not only because they take up much space, but more especially because of their liability to tip over and the fact that frequently the spacing of the shelves is such that they can be placed in an upright position only with some difficulty. The invention is especially concerned with this problem and it aims to devise an apparatus for supporting bottles in a refrigerator in such a manner that their 10 interference with other articles in the food chamber will be minimized. It is also an object of the invention to devise an article of this character which will hold bottles in a definite and fixed position in the refrigerator and which can be 15 used in practically any of the more common refrigerator constructions.

20

The nature of the invention will be readily understood from the following description when read in connection with the accompanying drawing, and the novel features will be particularly pointed out in the appended claims.

In the drawing,

Figure 1 is a front elevation of a refrigerator showing the food compartment or cooling chamber open, and illustrating a rack embodying this invention properly located in said chamber;

Fig. 2 is an angular view of the rack above mentioned;

Fig. 3 is a side view of said rack; and

Fig. 4 is an end view of the rack.

Referring more especially to Figs. 2, 3 and 4, it will be seen that the rack there shown is provided with two pockets or cradle-like recesses each adapted to receive a bottle and to support it in a reclining position. One such bottle is indicated in dotted lines at B, Fig. 3. Preferably the rack is made of wire elements or members. As shown, it comprises three curved wires 2, 3 and 4 bent to form two adjacent curved portions and all held in alignment with each other by horizontal side rods 5—5 and bottom wires or rods 6—6. These wires or rods are welded, brazed or soldered to the curved wires at their points of intersection with the latter. The curved portions of each of the wires 2, 3 or 4 are substantially alike so that this arrangement produces a rack having the two pockets or recesses above mentioned.

For the purpose of supporting the rack in the food compartment of a refrigerator, the ends of the front and rear curved wires 2 and 4 are ex-

tended upwardly and terminate in hooks 7 which are adapted to be engaged with the cross wires of a refrigerator shelf, such as those shown at 8 in Fig. 1. When the rack is so suspended in the food chamber it will support bottles in a horizontal position immediately below the refrigerator shelf to which the rack is attached. The lateral curvature of the pockets is such that any substantial sidewise movement of the bottles is prevented. In addition, the rearward movement 5 of the bottles is definitely limited by stops 9—9 provided at the rear end of each pocket. These stops may conveniently be formed by making the two elements 6 of a pocket parallel to each other and connecting them at one end by a bridge piece 10 which is bent at approximately right angles to the elements themselves, as will be clear from an inspection of the drawing. It will be observed that certain of these wires 6 which extend lengthwise 15 of the pocket form a track on which the bottle 20 may slide into or out of the pocket.

Such a rack, therefore, supports bottles closely adjacent to the lower side of a refrigerator shelf where they offer a minimum of interference with the placing of other receptacles, containers or 25 articles of food in the refrigerator. In other words, the bottles occupy none of the shelf space. Several such racks may be used in the refrigerator, therefore, without interfering in any way with the normal use of the space in the food chamber for other purposes. In addition, the other racks may be conveniently moved from 30 one location to another in the chamber.

While I have herein shown and described a preferred embodiment of my invention, it will be understood that the invention may be embodied in other forms. For example, the rack can be made of pressed metal, but I prefer the wire construction for the reason that it can be manufactured more economically. Regardless of 35 whether the rack is made of pressed metal or wire construction it will be quite evident, due to its curved construction and the nature of the material from which it is made, that the rack is 40 inherently flexible in lateral directions.

Having thus described my invention, what I desire to claim as new is:

1. A rack adapted to be suspended from a refrigerator shelf and comprising a support having crossed wires secured together, some of said wires 45 cooperating with others extending transversely to them to form a plurality of separate pockets each adapted to receive and hold a bottle in a reclining position, said pockets lying side by 50 side parallel to each other and having a dividing 55

- means between them to hold adjacent bottles separated from each other, and arms extending upwardly from said support and provided with hook portions at their upper ends for engaging 5 said shelf and suspending the rack therefrom.
2. A rack adapted to be suspended from a refrigerator shelf and comprising a support having crossed wires secured together, some of said wires being bent and cooperating with others extending 10 transversely to them to provide a plurality of cradle-like pockets lying side by side and parallel to each other but separated from each other, each of said pockets being adapted to receive and support a bottle in a substantially horizontal position, a stop at the rearward end of each pocket to engage the end of the bottle therein, and arms extending upwardly from the sides of said support adjacent to the corners thereof and each 15 terminating in a hook for suspending the rack
- from a refrigerator shelf and holding it in an approximately horizontal position immediately below said shelf.
3. A rack adapted to be suspended from a refrigerator shelf and comprising a support made essentially of crossed wires secured together, some of said wires cooperating with others extending transversely to them to form a plurality of separate pockets each adapted to receive and hold a bottle in a reclining position, said pockets lying side by side parallel to each other and having a dividing means between them to hold adjacent bottles separated from each other, certain of said wires extending longitudinally of said pockets and being supported on transverse wires to 10 provide a track on which a bottle may slide into and out of the pocket. 15
